PIEZO-ELECTRIC DEVICE

Original Filed Oct. 14, 1927

UNITED STATES PATENT OFFICE

CHARLES B. SAWYER, OF CLEVELAND HEIGHTS, OHIO, ASSIGNOR, BY MESNE ASSIGNMENTS, TO THE CLEVELAND TRUST COMPANY, OF CLEVELAND, OHIO, A CORPORATION OF OHIO

PIEZO-ELECTRIC DEVICE

Application filed October 14, 1927, Serial No. 226,139. Renewed November 18, 1930.

This invention relates to a new and improved form of piezo-electric sound reproducer and the method for constructing the same.

5 An object of the invention is to provide a piezo-electric device which will faithfully reproduce impressed electric voltages as sound waves, and which inherently magnifies the mechanical motion of the piezo-electric element without the use of leverages or linkages.

10 A further object of this invention is to provide an apparatus in which the piezo-electric elements are protected from mechanical shocks.

15 Another object of this invention is to provide a frame member in which a section of piezo-electric material is mounted so that expansion of said material upon the application of an electromotive force will cause the frame member to move in direct proportion to the electromotive force.

20 Another object of the invention is to provide a frame member in which the effect of temperature changes of the device is compensated for.

25 In utilizing the piezo-electric effect of crystals in order to transform electrical energy into sound, it is desirable to have the piezo-electrical material so arranged that comparatively small mechanical movement of the material will cause a relatively large movement of a sound radiating member. One of the best ways of accomplishing this 30 is to arrange two piezo-electric crystalline portions or sections so that when an actuating electromotive force is applied to the device one crystalline section will expand and the other crystalline section will contract in a 35 direction to cause a bending movement of the device to actuate a sound radiating member. Thus, the action of these crystalline sections is combined in a unit for producing a magnified mechanical movement.

40 45 It is also desirable to keep the moving parts as light as possible with respect to the force acting upon them. In other words, the ratio of the mass to the force, or the weight per gram centimeter torque should be kept 50 as small as possible. To this end the moving

parts should be made of some light material, such as aluminum or magnesium which has relatively low specific gravity.

Certain difficulties, however, are met with in attempting to utilize the piezo-electric effect of crystalline materials of the Rochelle salt type owing to the fact that their coefficient of thermal expansion is relatively large and upon a fall in temperature the contraction of the material is greater than the contraction of any metal with which it may be associated. This tends to produce fracture if the crystalline section is rigidly attached, as crystalline material of the Rochelle salt type is not very strong in tension, and is somewhat fragile upon the imposition of a sudden shock, although it will stand comparatively large amounts of compression. Metals such as aluminum or magnesium are very advantageous to use in this connection as they have a relatively large thermal expansion, thus minimizing the amount of compensation necessary.

In the drawings:

Figure 1 is a front elevation of my device. 75

Fig. 2 is a side elevation with a conical sound radiating member attached.

Fig. 3 is a diagrammatic view showing the movement of the device to which the sound radiating member is attached. 80

The device comprises a frame 1, preferably made of aluminum, magnesium, or similar light metal or light metal alloy. The frame 1 includes an actuating member 2 for a sound radiating element 3 which is shown to be of the conical type. The sound radiating element is secured to the actuating member 2 by means of any suitable securing means, such as a set screw 4, which clamps the actuating pin 5 in the hole 6 of the actuating member 2. The actuating member 2 preferably includes a thin metal section 7 which connects it with the base or supporting member 8. 85

The actuating member 2 and the supporting member 8 are provided with abutments or shoulders 9, 10, 11 and 12, between which may be mounted portions or sections 13 and 14 of piezo-electric material, so that the crystalline sections 13 will engage the shoul- 100

ders 9 and 10, and the crystalline section 14 will engage the shoulders 11 and 12 and cause movement of the actuating member 2 in a direction substantially transversely to the direction of expansion and contraction of the sections 13 and 14.

Each of the crystalline sections 13 and 14 is so cut from a crystal of piezo-electric material that when one side of a section is electrified positively with respect to the opposite side, the section will tend to expand longitudinally, and when the polarity is reversed, it will tend to contract longitudinally. Thus, if an alternating electromotive force is applied to the opposite faces of the section, the section will contract and expand longitudinally at a frequency corresponding to that of the applied electromotive force.

The crystalline sections 13 and 14 are also preferably arranged between the shoulders so that when the inner surfaces are at a potential different from the outer surfaces, one crystalline section expands longitudinally and the other contracts longitudinally, and this results in causing the actuating member 2 to have a maximum movement substantially transversely to the direction of expansion and contraction of the sections 13 and 14, as shown diagrammatically in Fig. 3.

The support 8 is preferably provided with holes 15 and 16 to facilitate connecting the support by any suitable means such as bolts 15^a and 16^a to a block of heavy material, such as the block 17 of lead in order to provide a relatively large mass that will not be responsive to small vibrations, thus insuring that substantially all of the movement caused by the expansion and contraction of the crystalline sections will be transmitted to the actuating member 2.

Suitable electrodes 18 and 19 of a thin conductor, such as tin foil, are secured to the outside faces of the crystalline sections in any suitable manner, such as by shellac or paraffin, but extend only to a point below the top and above the bottom of said crystalline sections 13 and 14 in order to leave a sufficient gap between the ends of these electrodes and the frame which forms the other electrode of the device. A suitable connector, such as a light spring clamp 20, connects the electrodes 18 and 19, and is provided with a lead 21 for connection to an outside source of electromotive force. The frame is also provided with a lead 22, which provides the other terminal for connection to the source of electromotive force.

In order to minimize the effect of the expansion and contraction of the crystalline sections 13 and 14 of Rochelle salt type upon changes of temperature which is greater than that of the light metal frame, it is preferable to mount the crystalline sections between the actuating member 2 and the supporting member 8 under compression. One method of ac-

complishing this is to apply a force to the actuating member 2 and the support 8 so as to place the thin metal section 7 in tension. The latter, however, is not stretched sufficiently to approach its elastic limit. While it is still in tension, the crystalline sections 13 and 14 are placed in position between the actuating member 2 and the support 8, and if they are cemented in position the cement is allowed to harden before the tension is released.

The crystalline sections 13 and 14 are preferably selected of such length so that they will not permit the metal to return to its normal position, thus keeping the thin metal section partially in tension and placing the sections under longitudinal compression.

The result of this arrangement is to practically eliminate the ill effects of temperature changes. If the temperature is raised, the crystalline sections expand more than the thin metal section 7, and the compression of the crystalline sections is increased and the thin metal section 7 is stretched a little more. Since the crystalline sections withstand compression much better than tension, and since the thin metal section can be stretched still further without exceeding the elastic limit, no harmful effects follow the temperature rise. If, on the other hand, the temperature falls below the temperature at which the device was assembled, the crystal plates contract faster than the thin metal section, due to the fact that they have a greater thermal expansion coefficient, but the thin metal section has an additional shortening due to the release of the tension and thus maintains the crystalline sections under some compression between the shoulders.

It will be seen that it is preferable to have the vane 7 relatively thin, so that it will not cause too great a compression on the crystalline sections 13 and 14.

It will also be seen that a similar result can be obtained by assembling the device at a temperature below any to which the device will be exposed, which will, of course, due to the greater expansion of the crystalline sections upon temperature rise, place the metal section 7 in tension at normal temperature.

In cases where this stretching was not employed, the crystalline sections were often cracked when the temperature was reduced, owing to the tension developed, as plates made from crystals of salts of the Rochelle type are comparatively weak in tension. In cases where cracks did not develop, the musical reproduction sometimes became very poor, due to the loosening of the crystalline sections from the metal parts.

It should be noted, however, that the crystalline elements should not be placed in too great compression as this may impair the musical reproduction.

It is preferable to cement the ends of the crystalline sections 13 and 14 to the actuating

member 2 and the support 8 in order to compensate for any slight differences in length between the crystal portions, and in order to hold them securely in place between the shoulders 9, 10, 11 and 12. It may also be desirable to cement the crystal sections to the faces of the thin metal section 7.

In constructing this device, any suitable cement for connecting the crystal sections to the metal frame may be used such as Canada balsam, duco, copper mercury amalgam, or others. The copper mercury amalgam is especially useful in securing a good contact at the ends, as it expands slightly upon hardening.

If an electrically conductive cement be used it should not overlie the outside faces of the crystalline sections 13 and 14 sufficient to make contact with the electrodes 18 and 19.

It will also be seen that by making the vane 7 and crystalline sections 13 and 14 progressively smaller in a direction away from the support 9, the stresses caused by the bending moment will be more nearly uniform. Moreover, the mass to be moved will be progressively reduced in those regions where the motion becomes a maximum.

If desired, the whole device may be coated with a protecting varnish or duco after the terminal clip 20 is applied.

When an electromotive force is applied, the tinfoil electrodes upon the outside of the crystal plates have a potential difference from the inside thin metal strip or inside faces of the plates, and an electrostatic field is set up in the plates in opposite directions, and the plates being oriented as previously described, one plate contracts and the other expands, producing a bending moment which deflects the metal frame and causes a movement of the actuating member 1 relative to the support 9. Since the support 9 is held fixed by the lead block the motion is transmitted to the conical sound radiating element. When the applied electromotive force is reversed, the movement of the sound radiating element is reversed.

The movement of the sound radiating element is much larger than the actual expansion or contraction of the crystalline section as may be readily understood by referring to Fig. 3. Here the full lines show the normal position of the device and the dotted lines show in an exaggerated form the position of the device when an electromotive force has been applied to the terminals. The crystalline section on one side is expanded longitudinally and the crystalline section on the other side is contracted longitudinally, thus exerting unequal pressure on the shoulders of the actuating member. Since a geometrical element of the central vane remains at constant length and the crystalline portion on one side is expanded and on the

other side is contracted, a bending moment is produced which imparts a tilting motion to the actuating member of the metal frame, thus moving the conical sound radiating element in a plane substantially at right angles to the plane of the crystalline sections.

While the effect of the sections on the shoulders resulting in the tilting of the actuating member is probably increased when the sections 13 and 14 are caused to adhere closely to the central vane, it has been found that when the sections are not secured to the central vane, a sufficient movement of the actuating member may be obtained to produce satisfactory operation.

It will be noted that the thin vane 7 which connects the base and actuating member 2 affords a reinforcement for the crystalline sections 13 and 14, and the sections are further protected by the shoulders 9 and 12 of the base and the shoulders 10 and 11 of the actuating member 2, so that the sections are less susceptible to breakage from mechanical shocks. The vane 7 also affords a convenient structural member to which the sections may be secured, but it is to be understood that any method of securing the sections for longitudinal expansion and contraction, and for causing them to move the actuating member 2 with respect to the base, can be used.

While it is preferable to use a light metal for the frame, it may be noted that other light material having a suitable strength and rigidity to cooperate with crystalline elements may be used.

It will also be seen that since only portions of a crystal need be used in accordance with my invention, economy of piezo-electric material is obtained, as those portions may be cut from imperfect crystals or a fragment of a crystal.

Since the vane and shoulders provide a mechanical support and reinforcement for the crystalline sections, it is unnecessary to embed the ends of the crystalline sections in the cement used to attach them to the frame, and consequently the entire length of the section remains effective for a producing motion.

Furthermore, it is to be understood that the particular forms of apparatus shown and described, and the particular procedure set forth, are presented for purposes of explanation and illustration, and that various modifications of said apparatus and procedure can be made without departing from my invention as defined in the appended claims.

What I claim is:

1. A piezo-electric device comprising, in combination, a metallic frame including a fixed base and an actuator connected thereto by a longitudinally resilient connecting means, a plurality of expansible members mounted between the base and actuator under compression, said expansible members being so mounted that upon the application of

electrostatic fields simultaneous expansion and contraction takes place, whereby a movement of the actuator in a plane substantially perpendicular to the plane of the expansible members is produced.

2. A piezo-electric device comprising, in combination, a frame of relatively light metal including a fixed base and an actuator connected thereto, said base and actuator being provided with opposing abutments, a plurality of crystalline sections of piezo-electric material mounted between said abutments to normally engage the same, said sections being so mounted that when subjected to electrostatic fields simultaneous expansion and contraction take place, whereby a movement of the actuator in a direction substantially transverse to the direction of expansion is produced.

20 3. A piezo-electric device comprising, in combination, a metallic frame including a base and an actuator connected thereto by a longitudinally resilient connecting means, a pair of sections of piezo-electric material mounted between the base and actuator under compression so that upon the application of an electromotive force to the faces of the sections one of the sections will expand and the other will contract, whereby the actuator is caused to vibrate in a direction transverse to the direction of expansion.

35 4. A piezo-electric device comprising, in combination, a base and an actuator, said base and actuator having opposing abutments and being connected together with a longitudinally resilient connecting means, a pair of sections of piezo-electric material mounted between said base and actuator under compression, and in position to cause movement 40 of the abutments of the actuator in a direction substantially transverse to the direction of expansion and contraction of the piezo-electric sections, means for applying an electromotive force to the faces of the piezo-electric sections to cause the expansion of one and the contraction of the other simultaneously, and an acoustic element connected to said actuator.

50 5. A piezo-electric device comprising, in combination, a base and an actuator, said base and actuator being connected together by a relatively thin, longitudinally resilient connecting means of relatively light metal, a pair of sections of piezo-electric material secured to said connecting means and having their opposite ends normally engaging said base and actuator, electrodes attached to the outer surface of said sections so that upon 60 the application of an electromotive force to the faces of the sections one section will expand and the other will contract to cause movement of the actuator with respect to the base in a direction substantially transverse to the direction of expansion and contraction

of the sections, and a sound radiating element secured to said actuator.

6. A piezo-electric device comprising, in combination, a fixed base and an actuator, said base and actuator being connected together by a relatively thin, longitudinally resilient connecting means, a pair of sections of piezo-electric material disposed adjacent said connecting means and adapted to engage the base and actuator, said sections being secured to the base and actuator and being under compression, so that upon the application of an electromotive force to the faces of the sections one section expands and the other contracts to cause movement of the actuator with respect to the base in a direction substantially transverse to the direction of expansion.

7. The method of producing a piezo-electric device having a metallic frame, comprising an actuator connected by a longitudinally resilient means to a fixed base, tensioning the longitudinally resilient connecting means, positioning sections of piezo-electric material between the base and actuator, and adjacent the connecting means, cementing the sections in position, and releasing the tension on the connecting means after the cement has hardened.

8. The method of producing a piezo-electric device having a metallic frame, comprising an actuator connected by a longitudinally resilient means to a fixed base, tensioning the longitudinally resilient connecting means, positioning sections of piezo-electric material between the base and actuator in opposed relation, so that upon the application of an electromotive force one section will expand and the other will contract, and releasing the tension on the connecting means, whereby said sections are placed under compression between the base and actuator.

9. A piezo-electric acoustic device comprising a frame including a base, an actuator for an acoustic diaphragm and a longitudinally resilient connecting means connecting the actuator and base, sections of piezo-electrical material of the Rochelle salt type disposed under compression between the base and actuator for causing movement of the actuator upon the application of electromotive force to the piezo-electric material, said actuator and connecting means being constructed of metal having a relatively low specific gravity and having a relatively high coefficient of thermal expansion.

10. A piezo-electric acoustic device comprising a frame including a base, an actuator for an acoustic diaphragm and a longitudinally resilient connecting means connecting the actuator and base, sections of piezo-electric material of the Rochelle salt type disposed under compression between the base and actuator for causing movement of the actuator upon the application of electromotive force to the piezo-electric material, said actuator and connecting means being constructed of metal having a relatively low specific gravity and having a relatively high coefficient of thermal expansion.

tive force to the piezo-electric material, said connecting means being constructed of metal having a relatively low specific gravity and having a relatively high coefficient of thermal expansion.

5 11. In a loud speaker, in combination, a metallic frame including a base and a support, a sound reproducing surface carried by said support, said support and base being connected together by a relatively thin longitudinal member and being provided with opposing abutments, a plurality of crystalline sections of piezo-electric material mounted between said abutments, said sections being mounted so that when subjected to electrostatic field simultaneous expansion and contraction takes place, whereby a bending movement is produced and said support transmits motion directly to said sound reproducing surface.

10 12. In a loud speaker, the combination with a sound reproducing surface, of a base and a support connected together, said sound reproducing surface being carried by said support, sections of piezo-electric material disposed under compression between the base and support for causing vibration of the support upon the application of an electromotive force to the piezo-electric material, said 15 piezo-electric sections being arranged to simultaneously expand and contract to cause a transverse vibration of the support upon the application of electromotive force, and a consequent vibration of the sound reproducing surface.

20 13. A piezo-electric device comprising, in combination, a frame, including a fixed base and an actuator connected thereto by a resilient connecting means, said base and actuator being provided with opposing abutments, a plurality of crystalline sections of piezo-electric material mounted between said abutments under compression, said sections being 25 so oriented that they are disposed in opposed electrostatic relation, and so positioned between the abutments that a longitudinal expansion of one section is accompanied by a longitudinal contraction of an opposed section, said sections of piezo-electric material 30 having electrodes secured to the outside surfaces of the crystalline sections.

In testimony whereof I affix my signature.
CHARLES B. SAWYER.
